Inventor

Grover C. Ramsey,

By J. Hanson Boyden

Attorney.

UNITED STATES PATENT OFFICE.

GROVER CARLO RAMSEY, OF GASTONIA, NORTH CAROLINA.

FIRE ALARM.

Application filed May 19, 1925. Serial No. 31,826.

This invention relates to electric fire alarms and more particularly to alarms of that class which are automatically set into operation by the heat of a fire.

In some of its aspects, the present invention may be considered a further development of that set forth in my prior Patent, No. 1,331,277, dated February 17, 1920, in that I preferably employ a similar structure as part of my present apparatus.

In my said prior patent, I have illustrated and described a housing for an automatic sprinkler head, such housing having a wall of combustible material such as celluloid, adapted to become quickly ignited in the event of fire, and by the heat of its combustion, to release the automatic sprinkler head. In the present invention, I utilize this same housing to operate an electric fire alarm.

In order that the invention may be readily understood, reference is had to the accompanying drawings, forming part of this specification, in which:—

Figure 1 is a vertical sectional view through my improved apparatus, showing also the circuit connections; and

Figure 2 is a transverse section on the line 2—2 of Figure 1.

Referring to the drawings in detail, my improved housing or sprinkler head chamber, above referred to, comprises a body 1, made of sheet or cast metal, and having one flat side in which is formed a slot 2, to receive the water pipe. One end of the body may be beveled as indicated at 4, and the side opposite the slot 2 is arched or rounded, as shown at 3. At each side of the flat or base portion are provided a pair of spaced flanged members 5, constituting between them a slot or groove, as clearly shown in Figure 2. Into these slots or grooves are inserted the longitudinal edges of an arch-shaped relatively rigid sheet 6, such sheet

fitting within and conforming to the arch-shaped portion 3 of the body and being formed of celluloid, paper, or other readily combustible material. The housing above described is preferably mounted against a wall or partition A within the compartment to be protected. Mounted on the opposite side of this partition is a switch box B containing the circuit closer now to be described. This circuit closer consists of a leaf spring 7, rigidly secured at one

end to an insulated screw or bolt 8. Near the free end of the spring 7 is mounted a contact point 9. This is urged by the spring into engagement with an insulated screw or post 10. When the contacts 9 and 10 are in engagement, an electric circuit will be closed including the wires 11 and 12, battery 13, and suitable signaling devices, such as a bell 14 and lamp 15. These latter may be located at any desired point, or, if preferred, they may be substituted by a suitable relay. As shown in the drawing, the contacts 9 and 10 are normally held apart, and the spring 7 under tension by means of a link or wire 16 having one end in engagement with the spring 7 and the other end attached to and supported by the arched combustible sheet 6, the link 16 extending through an opening 17 in the partition A.

Upon the occurrence of fire, the sheet 6 will readily ignite and burn, thus destroying the support for the link 16, whereupon the spring 7 will straighten out, thus bringing the contacts 9 and 10 together, and operating the signal devices.

An automatic sprinkler head 18 secured to a water pipe 19, as shown in dotted lines, may or may not be used in connection with the circuit closer and signals. If an automatic sprinkler head is employed, it should be noted that the sprinkler head and the circuit closer are both operated by the same element, namely, the celluloid sheet.

What I claim is:—

1. The combination with a circuit closer biased toward closed position, of a chamber having a wall of celluloid, a partition between said chamber and circuit closer, and a link extending through an opening in said partition, said link being supported at one end on said wall, and at its other end engaging said circuit closer to hold it open.

2. The combination with a circuit closer biased toward closed position, of a chamber adjacent thereto and comprising a base, and a flat sheet of celluloid or the like, supported at its opposite edges on said base, and bent into the form of an arch, and means supported by said sheet for normally holding said circuit closer open.

3. The combination with a circuit closer biased toward closed position, of a chamber adjacent thereto comprising a base, and

an arched wall consisting of a flat sheet of celluloid, bent into bow shape, the opposite edges of said sheet being supported on said base, and the end of the said chamber formed by said sheet being open, an automatic sprinkler head mounted in said chamber, and adapted to be operated by the heat

of combustion of said sheet, and means supported by said sheet for normally holding said circuit closer open. 10

In testimony whereof I affix my signature.

GROVER CARLO RAMSEY.
